UNITED STATES PATENT OFFICE.

BRUCE FRANK PUFFER, OF GARDEN CITY, NEW YORK.

METHOD OF PRODUCING REMADE PICTURES.

Application filed August 16, 1921. Serial No. 492,731.

To all whom it may concern:

Be it known that I, BRUCE FRANK PUFFER, a citizen of the United States, and a resident of Garden City, Long Island, in the county 5 of Nassau and State of New York, have invented a new and Improved Method of Producing Remade Pictures, of which the following is a description.

My invention while capable of a wider use 10 is especially applicable to the production of motion picture films and the description in the main will be directed to the carrying out of the invention in connection with motion pictures.

15 It is well recognized that attempts at retouching, altering, or otherwise modifying motion picture films, are handicapped and greatly limited by the exceedingly small size of the images and as a consequence, pictures are exhibited whose defects are pronounced and apparent but which are impossible of being properly remedied by eliminating or modifying the undesirable factors.

The general object of my invention is to 25 produce a motion picture film or like photographically produced medium vastly improved over those now produced and projected and to provide a method and means available for the purpose and of such a character as to establish conditions making unfailingly for the production of a recreated film from an existing film and characterized by absolute correspondence between the recreated product and the original film with 30 respect to exactness of register and correctness of sequence but with all defects eliminated or modified.

Specifically, a most important object of 40 my invention is to make it possible to eliminate, retouch, "reduce" by chemical action, or otherwise modify by various methods the defects in a picture that are subject to treatment as in ordinary photography, thereby freeing the motion picture films or similar 45 small photographic media from the limitations now attending them with respect to the possibility of correction or modification.

The above and other objects as will appear 50 are attained by my improved method and means involving the forming of an enlarged reproduction of each picture in a film, employing for the purpose a sensitized photographic medium or media in the form of a long roll film, cut celluloid film, glass plates, 55 sensitive paper, or any other element capable of receiving and recording an enlarged

image as in the ordinary process of making enlarged photographic negatives or positives, and in a manner to obtain identical repetition of register and position in the successive pictures whereby a picture will correspond in its enlarged state with the original picture and present a precise duplication of the image as framed through the aperture plate of an ordinary motion-picture camera. The increased visibility of the enlarged negative or positive thus obtained affords me the widest liberty in the retouching, etching, chemically "reducing" locally, or otherwise altering the image, or, I am 60 afforded liberty to obtain a modified final enlargement by combining two or more developed and fixed films or plates bearing enlargements of pictures of the original film, or bearing enlargements of portions of two 65 or more motion picture films, which enlarged films or plates may be superposed for reproduction to obtain a resultant composite picture; or by projecting two or more pictures or portions thereof onto the same light sensitive medium before developing; the sensitive medium being a roll film, cut celluloid film, glass plates, or paper as the occasion 70 may determine.

Having thus produced the modified enlarged negatives or positives of the pictures of the original motion picture film, or equivalent related pictures, I photograph such enlargements through the medium of a motion-picture camera, reducing thereby 75 the pictures back to the original standard or safety standard size, on a motion picture film for example, one frame or exposure at a time by stop motion, i. e. one turn of the camera crank to a picture and employing 80 evenly transmitted and diffused light back of the enlarged negative or positive and of sufficient intensity to properly expose each 85 separate frame or image onto ordinary motion picture films, or equivalent media for 90 producing sequentially related pictures and under the exact conditions under which the enlargements were made, by requiring that the photographing of the remade pictures (the negatives or positives) be carried out 95 without any disparity of position, having in view the position of the sensitized media in the making of the enlargements and the position of the improved negatives or positives when employed for the reproduction 100 by means of a motion-picture camera.

The stated correspondence of position is

attained by making it impossible to displace the negatives or positives along their own plane when emplacing them for photographic reproduction (by the motion-picture camera) as compared with the original position of the sensitized media in the projection of the originals for enlargement.

The result is a remake or re-created film from which the defects present in the original film are eliminated to the same degree and in the same manner as is possible in still photography wherein by retouching, etching, etc., facial imperfections, for example, are obliterated, while at the same time the remake pictures are characterized by an absolute correspondence with the original film pictures as to register, etc.; the paramount desideratum being at the same time attained that the remake film preserves to the maximum degree the artistic results obtained in the original pictures only by superior talent and the exercise of great care and skill.

Reference is to be had to the accompanying drawings, it being understood that the drawings are merely illustrative of examples of instrumentalities that may be utilized in carrying out the invention.

Figure 1 is a sectional side view of a projecting machine largely conventionally shown and a fixed support in front of the same for holding a photographic medium onto which a picture to be enlarged may be projected, the view including light-producing means at the back of the support for reproducing the enlargement photographically in the original size, the view indicating the instrumentalities referred to as utilized for projecting the original picture of the films onto a sensitized medium on the support for obtaining an enlargement;

Figure 2 is a view of the instrumentalities shown in Figure 1 but indicating the same as employed for photographically reproducing from the enlargement for the production of remake motion pictures into the size of the original pictures;

Figure 3 is a front view of the support with a celluloid cut film thereon;

Figure 4 is a view similar to Figure 3 but with the sight opening in the support enlarged to conform to a larger film or plate;

Figures 5 and 6 are front views of the support as in Figure 3 but showing a manner of utilizing the same in the taking of a plurality of pictures in succession on a large film or plate;

Figure 7 is an enlarged vertical section of the support for the sensitive medium and the ground glass adjacent thereto, showing a frame employed in connection therewith to clamp the sensitive medium in position;

Figure 8 is a view similar to Figure 7 but omitting the clamp frame;

Figure 9 is a front view of the support modified for the holding of a glass plate;

Figure 10 is a vertical section on the line 10—10, Figure 9.

Referring to the illustrated instrumentalities there is shown in Figure 1 a projecting machine 15 which may be of any approved form, which machine includes a source of light 16 which is adapted to direct rays through a film 17 from which a remake film is to be produced in accordance with my invention. The light rays passing in the usual manner through a lens 18 are projected onto a sensitized receiving medium 19, the distance between the lens 18 and the medium 19 being so gaged as to result in a reproduction appearing upon the said medium enlarged to a desirable degree. After the medium 19 has been modified to eliminate or alter defective or undesirable factors such as a facial blemish or defect, and all the pictures on the film 17 having been similarly produced enlarged, I employ the same instrumentalities in the same mechanical relation to produce a remake film with pictures of the exact size of those in the original film for which purpose the projecting machine 15 is arranged as a camera, that is to say, a new unexposed film 20 is placed therein.

With the machine 15 arranged as a camera, the several enlarged mediums 19 are positioned in succession and in regular sequence on the support 23, and light from source 21 is transmitted through the opening 23^a in the support 23 and the enlarged medium 19 into the machine 15 and onto the sensitive film 20, the film 20 being advanced one frame or exposure at a time as new and successive enlargements are positioned on the support 23. In the photographing of the successive enlargements I have shown a source of light 21 at the back of the support 23 and have indicated a ground glass 22 that may be interposed, if desired, for the diffusion of the light. The support 23 has a sight opening 23^a and at the front of the support means is provided to hold the film or plate.

In the form shown in Figures 1 to 8, pins 24 project from the face of the support 23 above and below the sight opening and the film is formed with corresponding apertures to receive the pins, the arrangement insuring that the film as removed from the support 23 for developing, fixing, and retouching, or otherwise modifying, will, when restored to the support for photographic reproduction on a smaller scale, i. e. reducing down to ordinary motion picture film size, register exactly with its original position in its relation to the sight opening 23^a and the camera 15, and, as the successive enlargements 19 are reproduced on the film 20 in the regular order of the original motion picture film, the remake film will be produced in exact correspondence with the orig- 130

inal film. There is no limit to the treatment that may be accorded the enlarged negative or positive for effecting its betterment or changing the picture's composition 5 so that the remade motion picture will have none of the defects present in the original motion picture film; and it may be altered to suit the individual taste or requirements of the producer. My invention may be particularly employed for "close-ups" of persons of whom it is not possible in many instances, with unretouched films as now produced owing to the presence in the features 10 of the actors, of facial blemishes, effects of age, or the like. The invention permits of prolonging, by many years, on the screen, the careers of great dramatic artists and screen favorites, especially women, who, through the effect of time, have passed the first flush of youth and into the decadent period where faded beauty no longer attracts when shown too "close up". In the projecting of the pictures from the original negative or positive film 17 onto the successive sensitive media 19 on the support 23, the sight opening 23^a in the support 23 is occupied by an opaque (black) filling 23^c. The filling 23^c is removed for the passage 25 of the light from the source 21 through opening 23^a, thence through the lens 18 to the sensitive film 20. In the steps of reproducing onto the sensitive motion picture film 20, a transparent backing 23^b may be employed on support 23 at the front of the sight opening 23^a as a backing for the enlarged negative or positive 19 to insure the flatness of said negative or positive particularly in connection with the swing frame hereinafter described. 30 In Figure 3 I have shown a single cut film 19 of small size on the support 23 that may be taken for example as a 4×5 while in Figure 4 the support, 23^b, is shown with an enlarged sight opening 23^c and a correspondingly large cut film 19^a which may be taken as 8×10. 35 In Figure 5 is shown the manner of obtaining four small exposures on a comparatively large film 19^b by exposing one-quarter section at a time, two exposures being made in succession along a side of the film and the film then up-ended as in Figure 6 for the taking of two more exposures. The film 19^b is formed with pairs of holes 19^c 40 for each quarter section, each pair to register with the pins 24. The individual films may have identifying numbers, the film 19 in Figure 3 being shown as bearing the numeral 1, the film in Figure 4 being numbered 1^a, and the films in Figures 5 and 6 as 1^b. It is to be understood that the films in a series of pictures will bear numbers in arithmetical succession. The usual notches A in the films serve to position the same even 45 with the taking of a plurality of exposures

as in Figures 5 and 6. The supports 23, 23^b, etc. are permanently fixed by any suitable means such as an angle bracket 23^f at the base thereof.

In Figure 7 a frame 25 is shown hinged 70 at its lower end as at 25^a adjacent to the front of the support 23 so as to be swung upwardly at the front of the support 23 against the medium 19 to prevent the possibility of forward displacement or vibration of said medium, there being a sight opening 23^b of proper size in said frame. 75

In Figure 8 the medium 19 is supported by the pins 24 alone without the use of the clamp 25. 80

In Figures 9 and 10 the support, 23^d, having a sight opening 23^e is provided with an angle piece 27 at the bottom, and one side of the sight opening to support a glass plate 19^d and there may be a turnable spring catch 85 26 to engage the plate.

By the described invention it will be seen that I am enabled to eliminate or modify all the defects now necessarily permitted to remain in motion pictures of regular or standard sizes because owing to the greatly increased visibility of the enlargements they may be treated at will in every factor thereof and at the same time the invention provides for the reproduction of the film in 90 its essential features and with its exact register and sequence. 95

I would state in conclusion that while the illustrated example constitutes a practical embodiment of my invention, I do not limit myself strictly to the exact details herein illustrated, since manifestly the same can be considerably varied without departure from the spirit of the invention as defined in the appended claims; for example, any other suitable means may be employed for positioning the successive enlargements in register with each other and in precise correspondence with the projecting of the pictures from the originals. 100 105 110

Having thus described my invention, I claim:—

1. In a method of producing remade related pictures from existing related pictures, the steps of photographically producing enlargements of the several pictures on sensitized means, occupying in succession the same position, altering said enlarged pictures to obtain a modified image, and photographically reproducing the modified enlarged pictures in their original size while the enlargements are in the identical positions occupied by them in the photographic production of said enlargements. 115 120 125

2. In a method of producing remade related pictures from existing related pictures, the steps of photographically producing enlargements of the several pictures while occupying in succession the same position, altering said enlarged pictures to obtain a 130

modification of the image, and photographically reproducing the modified enlarged pictures while the enlargements are in the identical positions occupied by them in the photographic production of said enlargements.

3. In a method of producing remade related pictures from existing related pictures, the steps of successively photographically producing enlargements, in order, of the pictures to be remade while occupying the same position; altering said enlarged pictures to obtain modified images thereof; and photographically reproducing the modified enlarged pictures in the original size of the said existing pictures in the same order in which they were projected and while the enlargements are in the identical positions of the projected pictures in the photographic production of said enlargements.

4. In a method of producing remade pictures from a series of related pictures, the steps of photographically producing successive enlargements of the originals by projection of the same on a sensitized means; rectifying objectionable features in the enlargements; and photographically reproducing the rectified enlargements while in precise register as to position with the projected enlargements.

5. In a method of producing remade pictures from a series of related pictures, the steps of photographically producing in regular succession, enlargements of the originals by projection of the same on a sensitized means; rectifying objectionable features in the enlargements, and photographically producing remade pictures from said enlargements while constraining the latter to occupy successively the same position in precise correspondence with the plane of the sensitized means during the projection of the originals.

6. In a method of producing remade pictures from a series of related pictures, the steps of photographically producing successive enlargements of the originals by projection of the same on a sensitized means, rectifying objectionable features in the enlargements, and photographically reproducing the pictures in a remade series, from the enlargements in the sequence in which the corresponding pictures existed in the original series and in register with said pictures of the projected enlargements.

7. In a method of producing remade pictures from a series of related pictures, the steps of photographically producing successive enlargements of the originals by projection of the same on a sensitized means, rectifying objectionable features in the enlargements, and photographically reproducing the pictures in a remade series, from the said enlargements, in the same size as the originals, and in precise correspondence

as to register with the projected enlargements.

8. In a method of reproducing remade motion pictures, from a series of related motion pictures, the steps of photographically producing successive enlargements of the original pictures of the series by projection of the same in succession on a sensitized means altering the successive enlargements thus produced, and photographically reproducing the pictures from said enlargements in a remade series of motion pictures through a sight opening in correspondence as to area and position with the original projection of the picture in the photographic production of the said enlargements.

9. In a method of producing a series of remade related pictures, the steps of disposing sensitized media in succession in the same position; producing on said media while in the said position, enlargements of the pictures to be remade; modifying the enlargements entering into the remade pictures; and photographically reproducing on motion picture films from the enlargements in the positions the latter successively occupied in their original production, by transmitting evenly diffused light through said enlargement from the back onto sensitized receiving means in a motion-picture camera in front.

10. In a method of producing a series of remade related pictures, the steps of disposing sensitized media in succession in the same position, producing on said media while in the said position, enlargements of the pictures to be remade, modifying the enlargements entering into the remade pictures and photographically reproducing from said enlargements pictures to the original size, while said enlargements are in the position they successively occupied when produced, by directing light through said enlargements from the back onto sensitized receiving means in front.

11. In the production of a series of remade related pictures, the steps of supporting sensitized means in front of a motion-picture projecting apparatus, producing enlargements of the originals on said sensitized means, with the aid of said projecting apparatus, modifying the enlargements; converting said projecting apparatus to function as a motion-picture camera while in the same position and directing light through said modified enlargements from the back to a sensitized means in the motion-picture camera, while said enlargements are in precise correspondence as to register with the first-mentioned sensitive means during the projection of the pictures to said first sensitive means.

12. In a method of producing remade related pictures, the steps of photographically producing enlargements of the pictures to

be remade by projecting the same onto sensitized means; modifying the enlargements; and photographically reproducing the enlargements while in a position in exact register with said sensitized means in the projection of the pictures in obtaining the enlargements.

13. An apparatus for use in the production of remade related pictures, said apparatus including a projecting machine adapted to be arranged for functioning as a motion-picture camera, a support adapted to receive sensitized means for the photographic enlarged reproduction of the pictures, said projecting machine and said support having fixed relative positions, and means for transmitting light through the reproduced pictures when on said support onto a second sensitized means in said projecting machine when arranged as a camera, for again reproducing the pictures.

14. An apparatus for use in producing remade related pictures, said apparatus including a projecting machine adapted to be arranged to function as a motion-picture camera, a support adapted to receive sensitized means for obtaining an enlarged reproduction of the pictures, said projecting machine and said support having fixed relative positions, means to coat with the projecting machine when functioning as a motion-picture camera, for transmitting light through the enlargements onto the sensitized means of the motion-picture camera, and means associated with said apparatus for insuring the disposition of the produced enlargements thereon in precise correspondence with the position of said first sensitized means for receiving the projected images of the originals.

15. In an apparatus for use in the production of remade related pictures, a support in fixed position adapted to receive a sensitized medium and having an opening through which light may be caused to pass from the rear, means on said support to unfailingly dispose successive media in the same position on said support at the front; together with a source of light behind said support and a projecting machine positioned in front of the support in fixed relation to said support and adapted to project pictures in reg-

ister with said opening, the said projecting machine being adapted to be converted so as to function as a camera and adapted by reason of its fixed relation to the support to receive light passing through the opening of the support. 65

16. In an apparatus for producing remade related pictures, a support adapted to receive sensitized means for the production of enlargements, and to support the enlargements for production after modification of the pictures, said support having an opening for the passage of light therethrough from the back, and means on the front to engage and hold the sensitized means as well as the modified enlargement in one and the same precise position to effect exact repetition as to register. 70

17. In an apparatus for producing remade related pictures, a support adapted to receive sensitized means for the production of enlargements, and to support the enlargements for production after modification of the pictures, said support having an opening for the passage of light therethrough from the back, and means on the front to engage and hold the sensitized means as well as the modified enlargement in one and the same 75 precise position to effect repetition as to register; together with a frame adapted to clamp the sensitized means or enlargements engaged by said holding means.

18. In an apparatus for producing remade related pictures, a support adapted to receive sensitized means for the production of enlargements, and to support the enlargements for production after modification of the pictures, said support having an opening 80 for the passage of light therethrough from the back, means on the front to engage and hold the sensitized means as well as the modified enlargement in one and the same position to effect exact repetition as to register, 85 and a frame adapted to clamp the sensitized means or enlargements engaged by said holding means; together with transparent material at the front of the opening in the support to constitute a backing for the sensitized means or enlargement positioned on the support. 90 100

BRUCE FRANK PUFFER.
